UNITED STATES PATENT OFFICE.

JOHN HOFFER, OF MARIANNA, PENNSYLVANIA.

SAFETY DEVICE FOR ELEVATOR-CARS.

1,396,753.

Specification of Letters Patent. Patented Nov. 15, 1921.

Application filed March 8, 1920. Serial No. 364,055.

To all whom it may concern:

Be it known that I, JOHN HOFFER, residing at Marianna, in the county of Washington and State of Pennsylvania, a subject 5 of the former Hungarian Kingdom in the former Austro-Hungarian Empire, have invented or discovered certain new and useful Improvements in Safety Devices for Elevator-Cars, of which improvements the following is a specification.

My invention relates to improvements in safety devices for elevator cars. Its objects are simplicity and effectiveness.

The particular kind of safety device to be preferred will depend in some degree on the nature of the installation. In Letters Patent No. 1,324,451, granted December 9, 1919, I have shown and described a safety device operating by springs borne by the car itself; 20 and a device such as that is preferable where it is a matter of importance to keep the shaft as free of cables as possible. The device which I now am about to describe and claim involves the use of an extra cable, and it is 25 at the same time effective in service. It relates itself particularly to elevators in which the torque exerted by the loaded car upon the car raising and lowering drum is balanced, in part at least, by a counterweight. 30 This counterweight, a necessary part of the installation, I find convenient, as a source of power to operate, when the emergency arises, my safety device.

The invention is illustrated in the accompanying drawings. Figure I is a view in side elevation showing diagrammatically the essential parts of an elevator installation, and with my present invention applied; Fig. II is a view to larger scale, a transverse section 35 on the plane indicated by the dotted line II-II, Fig. I; showing in plan the gripping members of the safety device, with certain of the operating parts; Fig. III is a view similar to Fig. II, showing a variation 40 in detail; Fig. IV is a fragmentary view corresponding to Fig. I and illustrating a variation in another feature; Fig. V is a view corresponding to Fig. I, and showing an elevator to which my invention in another form is applied; Fig. VI is a view in 45 transverse section on the plane indicated by the line VI-VI, Fig. V; Fig. VII is a view of the gripping members and the immediately connected parts, of the structure shown 50 in Fig. V, seen in plan from below—that is it is a view in section on the line VII-VII,

but looking upward; and Fig. VIII is a view in section of a detail, on the plane of section indicated at VIII-VIII, Fig. V.

The car is shown at 1, its sustaining cable 60 at 2, and the guides between which it moves at 3. 4 is the driving drum, upon which the car-sustaining cable is wound, and which in turning raises the car and allows it to descend. This drum is ordinarily, though 65 not necessarily, placed at the bottom of the elevator shaft. The particular position of drum 4 will be such as, in the particular installation, is convenient. A counterweight 5 hung on a cable 6 exerts upon drum 4 a 70 torque in opposite direction, balancing more or less completely the torque of the car. This counterweight 5 may if convenient rise and descend in the same shaft with car 1, or in another shaft. This too is a matter 75 determined according to circumstance; in some cases, it is preferred to employ, not a weight 5 as such, but to hang two cars in counterbalance, so that each serves as a 80 counterweight for the other, relieving the drum of excessive torque.

The safety-stop device (and I shall first describe that shown in Figs. I, II, and III) includes immovable members, which conveniently take the form of posts extending 85 adjacent the path of car travel. The guides 3 may serve as such posts. Coöperating with such immovable members is a post-engaging device borne by the car, normally inactive, but upon the parting of the car-sustaining 90 cable brought into action, to engage the immovable members and stop the car. This post-engaging device is, according to my invention, brought into action with the aid 95 of the counterweight.

In the form shown in Figs. I-III, the car 1 carries a rotatable shaft 7, and to this shaft, or (as will ordinarily be the case) to a drum 8 mounted integrally upon shaft 7, a cable 9 is secured. This cable 9 extends over a sheave at the upper end of the elevator shaft, and is connected to the counterweight 5, after such manner as is shown, to the end that when cable 2 breaks, the weight of counterweight 5 and the weight 100 of car 1 will exert opposite pulls upon cable 9. Normally cable 9 runs freely over the sheaves which carry it, and it exerts no appreciable tension upon drum 8. But in case 105 the main cable breaks, then the opposite pulls just indicated will effect turning of drum 8 and shaft 7, and will by such turning 110

effect operation of the safety device. Here, as elsewhere, the term counterweight 5 will be understood to include another car in counterbalance with the car carrying the safety device.

The safety device may conveniently consist of a pair of post-engaging members 10, arranged on opposite sides of posts 3. These two members 10 are articulated together by shafts 11, which rotating cause the members 10 to approach one another. This may conveniently be done by screw-thread connection, the threads being so cut that as shafts 11 turn in one direction or the other members 10 will approach or recede from posts 3. Rotation is imparted to shafts 11 from shaft 7 in either of the ways shown: Fig. II shows beveled-gear connection; Fig. III shows sprocket-chain connection.

Provision should be made, to relieve drum 8 of the torque which otherwise would be exerted, when the car rises to the top of the shaft, by the weight of cable 9 hanging from its guiding sheaves. In Fig. I an arm 12 is shown, pivotally mounted on car 1, and at one end engaging a stop on cable 9. Swinging of arm 12 is resisted by a spring 13. The proportioning of parts is such that spring 13 will sustain the weight of cable 9, and under all normal conditions arm 12 will relieve drum 8 of tension; but upon the great pull exerted upon cable 9 in case cable 2 parts, then spring 13 will be insufficient; arm 12 will swing aside, compressing spring 13 as it swings, and the tension then exerted upon cable 9 throughout its length will come upon drum 8 and turn it.

An alternative device is shown in Fig. IV, where a short length of relatively weak line 14 holds slack the end of cable 9 adjacent drum 8. The line 14 is strong enough to carry the weight of cable 9; but it is so weak that when, upon the parting of cable 2, heavy strain comes upon it, it breaks; whereupon the strain then comes upon drum 8.

The structure of Figs. V, VI and VII requires but a few additional words of explanation. The posts here become T irons 3^a, arranged as shown; the post-engaging members become jaws 10^a pivoted one to another, after the manner of pairs of shears; the remote ends of the shear arms are pivoted to blocks 15 screw-threaded on shaft 11^a; and shaft 11^a is turned through beveled gears 55 from the sheave 8^a, around which the end of cable 9 is coiled. The sheave 8^a is borne on a vertical shaft 7^a, instead of on a horizontal shaft, as in Figs. I-III. The provision for normally relieving the safety device 60 of the weight of the connected cable is as particularly shown in Fig. V that of Fig. IV, rather than that of Fig. I. It is obvious that either of these alternate provisions might be employed, as the engineer might prefer.

Fig. VII shows means for releasing the

safety device after it has functioned and when, as may be assumed, the broken cable 2 has been replaced, and normal conditions are to be reestablished. The releasing means consist of a pinion 16 turned by a handle 70 (which may be removable) 17 meshing with pinion teeth on the under side of sheave 8^a. An equivalent releasing device may be applied to shaft 7 of Figs. II and III.

Regardless of the particular form which the safety device may assume, a pair of co-operating stop members 18 and 19 may be provided borne, the one on rope 9, the other on a stationary part of the structure, coming into engagement when the car reaches or passes beyond the lower range of normal travel, and effective by such engagement to operate the safety device, and to prevent descent of the car to the very bottom of pit or cellar, even though cable 2 be not broken.

The safety device as shown in Fig. I is arranged on the top of the car; as shown in Fig. V it is beneath the floor. It will be understood that either arrangement is permissible for either form of device. Local conditions will dictate, which arrangement is chosen.

In normal operation of the elevator the safety device is inactive; it is only when cable 2 parts and car 1 begins to fall that the device becomes active. Then whatever device may be present to relieve the safety device of any strain is swept aside, the opposing pulls of weight 5 and of the falling car come upon cable 9, and through it upon drum 8 (or equivalent sheave 8^a). The turning of this member brings the pairs of members 10 (or 10^a) oppositely into engagement with posts 3 (3^a). The impelling force tends to draw these members into tighter and tighter engagement with the posts, and so the falling of the car is checked or stopped.

I have described the invention in its application to such an elevator as is used in buildings and in mine shafts. It will be understood that it is applicable to elevator cars or cages of all sorts, in whatever location, whether moving vertically or on an incline.

In the ensuing claims I define the features essential to the practice of my invention. Beyond these essential features, the showing of the drawings is exemplary merely, and modifications in structure and arrangement are permissible.

I claim as my invention:

1. In an elevator installation the combination of a car, a car-operating drum, a car-sustaining cable connecting car and drum, a counterweight exerting upon said drum a torque opposite in direction to that exerted thereon by said car, a second drum borne by said car, a normally slack cable 130

connecting said counterweight and said second drum, a safety device borne by said car, and operative connection between the aforesaid second drum and said safety device, substantially as described.

2. In an elevator installation a car sustained by a cable and movable in predetermined path, and a safety device including a post extending adjacent the path of car travel, a safety cable extending from the car longitudinally of the path of car travel, and post-engaging apparatus borne by the car, said post-engaging apparatus including a sheave upon which the safety cable is coiled, said sheave being provided with pinion teeth, and a pinion capable of rotation at will engaging said teeth, substantially as described.

3. In an elevator installation, the combination of a car, a car-operating drum, a car-sustaining cable connecting car and drum, a counterweight exerting upon said drum a torque opposite in direction to that exerted thereon by said car, a safety device borne by said car, a safety-device cable connecting

safety device and counterweight, and means rendered ineffective on the parting of the car-sustaining cable normally relieving the safety device of the weight of the safety-device cable, substantially as described. 30

4. In an elevator installation, the combination of a car, a car-operating drum, a car-sustaining cable connecting car and drum, a counterweight exerting upon said drum a torque opposite in direction to that exerted 35 thereon by said car, a safety device borne by said car, a safety-device cable connecting safety device and counterweight, and a member of relatively small tensile strength connecting safety-device cable to car and 40 normally relieving the proximate end of the safety-device cable of strain, substantially as described.

In testimony whereof I have hereunto set my hand.

JOHN HOFFER.
